UNITED STATES PATENT OFFICE.

NAPOLEON J. PERRY, OF NASHVILLE, TENNESSEE, ASSIGNOR TO MAY HOSEY MILLS, OF NASHVILLE, TENNESSEE, A CORPORATION OF TENNESSEE.

PATTERN MECHANISM FOR KNITTING MACHINES.

Application filed September 13, 1920, Serial No. 409,981. Renewed February 3, 1928.

The object of my said invention is to provide an improved pattern mechanism for controlling the dial needles of a dial and cylinder rib knitting machine primarily of the type having a stationary needle cylinder and rotary cam ring, but not necessarily limited to such type. Reference is had to my co-pending application No. 348,071, December 29, 1919, for details of construction of the machine not here shown, the pattern mechanism here described being a modification of that of the application. It is particularly adapted for use in a machine for knitting plain fabric by either rotary or reciprocating knitting and also adapted to knit ribbed fabric, as in my said application.

Referring to the accompanying drawings, which are made a part hereof and on which similar reference characters indicate similar parts,

Figure 1 is an elevation of a portion of the machine,

Figure 2 a view of the pattern drum and its follower, looking from the left of Figure 1, and

Figure 3 is a section on line 3—3 of Figure 1, looking down.

In the drawings, 1 indicates the main cam shaft of a machine of the character stated, which will ordinarily carry means as at 2 for changing the motion of the machine from rotary to reciprocating and vice versa a speed-changing cam wheel 22, a drum, as 3 to control the yarn-feed, the picker mechanism, etc., and one or more ratchets 4 or like means for rotating it, substantially as in the patent to Mayo 726,178.

On the knitting head is a pinion 5 as in my application 348,071 adapted to control the cams of the dial cam plate, and a rack-segment 6 is adapted to be moved up and down to engage or not with the pinion as the knitting head rotates. The rack-segment is fixed to a rod 7 slidably mounted in a bearing in bracket 8, and has a plate 9 fixed to it and to another rod 10 also slidably mounted in bracket 8. The latter rod slides in an elongated slot 11 in plate 8 and holds the rack 6 and connected parts in proper radial position for engagement with pinion 5. An eccentric bearing 12 surrounding rod 7 serves to adjust the rod in any direction by rotation of the bearing, and thus adjusts the rack radially or circumferentially of the machine, or gives it a compound movement providing both radial

and circumferential adjustment in varying degrees. The bearing is held in place after such adjustment by set-screw 13.

The rod 7 rests at its lower end on a lateral extension 14 of a lever 15 and the lever has a spring 16 underneath for contact with the drum as in the Mayo patent. At certain intervals about the drum are affixed six screws 17 each adapted at a proper time to move the rack into engagement with the pinion and thus change the positions of the dial cams.

The details of my improvements may be changed in various ways. Different numbers of screws may be used according to the nature of work desired and projections may be formed on the drum in various ways to serve the same purpose, and other changes will suggest themselves to those skilled in the art.

Certain features are adapted for use in knitting machines of other types, as well as various other machines in which pattern mechanism is employed, the true scope of the invention being defined in the appended claims.

Having thus fully described my said invention, what I claim as new and desire to secure by Letters Patent, is:

1. In a pattern mechanism for dial and cylinder knitting machines adapted to produce either ribbed, plain circular or reciprocating work, as desired, a main cam shaft, a cam on the shaft to vary the direction of movement of the machine, a cam drum fast on the shaft, a rod movable by the cam drum, and a rack projecting laterally from the rod to engage and actuate a dial cam controlling pinion, substantially as set forth.

2. In a pattern mechanism for knitting machines, a slidable rod, means for moving it vertically, a rack at the upper end of the rod for engagement with a pinion on the knitting head and means for adjusting the rack radially and circumferentially relatively to the pinion.

3. In a pattern mechanism, a slidable rod, a cam to raise and lower the rod, a guide member, an eccentric bearing rotatably adjustable relatively to the rod, and engaging an opening in the guide member.

4. In a pattern mechanism for circular knitting machines, a rack for engagement with a rotating pinion, and means to adjust the rack radially and circumferentially of the machine comprising an eccentric bearing

connected to the rack and a fixed support for the bearing, substantially as set forth.

5. In a pattern mechanism for knitting machines, a cam, a vertically-slidable rod connected thereto for vertical movement, means at the upper end of the rod to engage with dial cam adjusting devices on the knitting head and means to adjust the upper end of the rod radially and circumferentially of 10 the machine.

6. In a pattern mechanism for knitting machines, a slidable rod, means for moving it vertically, a rack at the upper end of the rod for engagement with a pinion on the 15 knitting head and means for adjusting the rack radially of the knitting head, substantially as set forth.

7. In a pattern mechanism for controlling the dial cams of a rib knitting machine, a 20 main cam shaft having means thereon for controlling the speed and direction of the machine, a pattern drum fixed to the shaft having means for controlling the yarn feed, the instep cams and pickers, and having also 25 a series of studs thereon, a lever adapted to rest with its free end upon said studs, a rod extending upward from said lever, a rack

segment on said rod, and a star-wheel adapted to be engaged by said rack at predetermined intervals.

8. In a knitting machine, a cam rotatable about the axis of the machine, means whereby the position of said cam may be varied, a rod on the fixed frame of the machine having at one end an abutment adapted to operate said positioning means, pattern mechanism adapted to place said abutment in position to engage the positioning means for the cam, an eccentric sleeve providing a bearing for the rod and adapted for rotary 40 adjustment about the same, and means for supporting the sleeve, substantially as set forth.

9. In a pattern mechanism for knitting machines, a slidable rod, means for moving it vertically, a rack at the upper end of the rod for engagement with a pinion on the knitting head and means for adjusting the rack circumferentially of the knitting head, substantially as set forth.

In witness whereof, I hereunto set my hand at Nashville, Tennessee, this 9th day of September, A. D. nineteen hundred and twenty.

NAPOLEON J. PERRY.
